UNITED STATES PATENT OFFICE.

FRANK MILHENING, OF EVANSTON, ILLINOIS, ASSIGNOR TO J. MILHENING, INC., OF CHICAGO, ILLINOIS, A CORPORATION OF ILLINOIS.

DESIGN FOR A SCARFPIN.

Application filed March 6, 1924. Serial No. 8,856. Term of patent 7 years.

To all whom it may concern:

Be it known that I, FRANK MILHENING, a citizen of the United States, residing at Evanston, in the county of Cook and State of Illinois, have invented a new, original, and ornamental Design for Scarfpins, of which the following is a specification.

In the accompanying drawing, forming part of the specification—

Figure 1 is a front elevation, and Figure 2 is a side elevation of a scarfpin embodying the design.

I claim:

The ornamental design for a scarfpin as shown.

FRANK MILHENING.
